UNITED STATES PATENT OFFICE.

RICHARD GABRIELSKY, OF JERSEY CITY, NEW JERSEY.

TUNE SHEET OR DISK.

SPECIFICATION forming part of Letters Patent No. 690,264, dated December 31, 1901.

Application filed April 4, 1901. Serial No. 54,310. (No model.)

To all whom it may concern:

Be it known that I, RICHARD GABRIELSKY, a citizen of the United States, residing at Jersey City, in the county of Hudson and State 5 of New Jersey, have invented certain new and useful Improvements in Tune Sheets or Disks; and I do hereby declare the following to be a full, clear, and exact description of the invention, such as will enable others skilled 10 in the art to which it appertains to make and use the same.

This invention relates to a tune sheet or disk, and more particularly to the note teeth or projections of such a sheet for a mechanical musical instrument.

The object of my invention is to provide a tooth or projection in a tune sheet or disk of a strong and durable construction which will effectively resist the pressure and wear due to 20 the frequent contact thereof with the points of the star-wheel or contact-wheel or other part of a mechanical musical instrument.

In my tune sheet, disk, or band the teeth or projections are cut or stamped out by 25 means of a die from the body of a metal sheet and are each made with a vertical portion having a square outer end, also with a diagonal brace or stay attached to the rear face and to the metal sheet, the tooth and diagonal 30 brace being integral with the sheet. The diagonal brace or stay is attached at both its ends, being a continuous part of the metal in the tooth and sheet, so that it is not liable to displacement and will rigidly support the 35 tooth.

The details of construction of my improved tune-sheet with teeth or projections are illustrated in the accompanying drawings, in which—

40 Figure 1 represents a perspective view of a part of a tune disk or sheet made in accordance with my invention. Fig. 2 represents a vertical section, on an enlarged scale, of a tooth on line $x-x$, Fig. 4. Fig. 3 represents 45 a section on line $y-y$, showing the front face of a tooth. Fig. 4 represents a top plan view showing the top edge of the tooth and its brace. Fig. 5 represents a top plan view of 50 a portion of a metal sheet, indicating lines of the cut of exaggerated length made in stamp-

ing out the tooth and brace. Fig. 6 represents an elevation of a portion of a disk or sheet, a tooth, and a star-wheel.

The sheet or disk A or a band, plate, or cylinder is made of any suitable sheet metal, 55 and the note projections or teeth are struck up therefrom by means of suitable dies, which may be operated by hand or machinery. The note projection b is preferably made rectangular with a straight outer edge f and is provided at its rear face with a diagonal stay or brace c, which is also struck up from the metal sheet, being a continuation of the metal in the tooth and the sheet, as shown in Figs. 1, 2, and 5. In Fig. 5 the intersecting lines e , e' , and e'' 60 indicate the lines of cut made by the dies to form the tooth, and the lines n indicate the cut to form the stay or brace, the lines for the purpose of illustration being shown of exaggerated length. The dotted lines show where 70 the tooth and brace are bent. The tooth b is bent up into a perpendicular position, leaving an opening a, and the brace c into a diagonal or slanting position, as clearly shown in Figs. 2, 3, and 4. The tooth and its brace 75 may be cut and struck up from the metal sheet by one stroke or movement of the die. The diagonal brace c being placed midway between the lateral edges of the tooth and forming an integral portion thereof and metal 80 plate makes the tooth quite rigid and effectively supports it against bending. The tooth will be best supported in the middle, where it strikes against the teeth or points d of the star-wheel D, as shown in Fig. 6. It 85 will be noted that the front face of the tooth is plain and flat where it makes contact with the points or teeth of the star-wheel or sprocket-wheel and that the tooth is so rigidly supported that it will produce strong clear 90 tones in the instrument to which the tune sheet or disk is applied. It is also to be noted that the parallel cuts n , Fig. 5, extend up into the tooth portion b and to the rear thereof into the body of the metal sheet, so as to 95 form an effective brace and support for the tooth.

In practice the teeth b are not usually made so large as those shown in Fig. 1, and both the tooth and brace are struck up in a die, 100

in which operation the metal in the brace is upset or crowded and thickened, being thus strengthened.

Having described my invention, what I claim, and desire to secure by Letters Patent, is—

1. A tune sheet, disk or band having a note tooth or projection and a diagonal brace therefor attached at its ends and being a continuous part of the metal in the tooth and body of the sheet, substantially as described.
2. A tune sheet, disk or band having a perpendicular note tooth or projection and a diagonal brace struck up from the sheet metal and integral therewith, the brace being attached at its ends and a continuation of the metal in the tooth and body of the sheet, substantially as described.
3. A tune sheet, disk or band having a per-

pendicular note tooth or projection and a diagonal brace struck up from the sheet metal and integral therewith, the brace being attached midway between the lateral edges at the rear face of the tooth and to the body of the sheet, substantially as described. ²⁰

4. A note projection for a tune sheet, disk or band, composed of a square or rectangular portion and a brace portion made by parallel cuts extending into the tooth and rearward from its base into the body of the sheet, and ²⁵ bent into place, substantially as described.

In testimony whereof I affix my signature in presence of two witnesses.

RICHARD GABRIELSKY.
